Des. 215,377
Patented Sept. 23, 1969

215,377

TAPE DISPENSER

Oscar Miller, 4 Overlook Park, Newton
Center, Mass. 02159

Filed Nov. 28, 1967, Ser. No. 9,572

Term of patent 3½ years

Int. Cl. D19—02

U.S. Cl. D74—1

FIG. 1

FIG. 4

FIG. 2

FIG. 3

FIG. 1 is a side view of a tape dispenser showing my new design, the broken line showing of the tape in this view only being merely for illustrative purposes;

FIG. 2 is a left end view thereof;

FIG. 3 is a right end view thereof; and

FIG. 4 is a top view thereof.

I claim:

The ornamental design for a tape dispenser, as shown and described.
